UNITED STATES PATENT OFFICE.

FREDERICK WM. JONAS AND CHRISTOPHER STEELE SPOFFORD, OF STURGIS, MICHIGAN,
ASSIGNORS TO STURGIS STEEL GO-CART CO., OF STURGIS, MICHIGAN.

COLLAPSIBLE CARRIAGE.

1,161,315.

Specification of Letters Patent. Patented Nov. 23, 1915.

Application filed November 2, 1914. Serial No. 869,958.

To all whom it may concern:

Be it known that we, FREDERICK WM. JONAS and CHRISTOPHER STEELE SPOFFORD, citizens of the United States, residing at 5 Sturgis, Michigan, have invented certain new and useful Improvements in Collapsible Carriages, of which the following is a specification.

This invention relates to improvements in 10 collapsible carriages.

Our improvements relate particularly to folding carriages of the sulky or two wheel type, and we have shown the same in the accompanying drawings embodied in such a 15 structure. Certain features are, however, desirable for use and capable of ready embodiment in other types of children's carriages.

The main objects of this invention are: 20 First, to provide in a collapsible carriage an improved means for collapsing and erecting the wheel supports. Second, to provide an improved collapsible carriage which is very easily erected and collapsed and may be 25 erected by a person using one hand only. Third, to provide in a collapsible carriage an improved means for locking the carriage in its erected position. Fourth, to provide in a collapsible carriage of the sulky type 30 an improved foot rest. Fifth, to provide in a collapsible carriage of the sulky type an improved standard. Sixth, to provide a collapsible carriage having parts adapted as 35 rests or supports when the carriage is collapsed and upon which the collapsed carriage will stand in an upright position. Seventh, to provide an improved collapsible carriage having these advantages which is 40 comparatively simple and economical in structure and one which is very rigid when erected and very durable in that the parts are so arranged as to effectively withstand 45 the strains to which they are subjected in use.

Further objects, and objects relating to structural details, will definitely appear from the detailed description to follow.

We accomplish the objects of our invention by the devices and means described in 50 the following specification.

The invention is clearly defined and pointed out in the claims.

A structure which is a preferred embodi-

ment of our invention is clearly illustrated in the accompanying drawing forming a 55 part of this specification, in which:

Figure I is a front perspective view of a structure embodying the features of our invention, the tongue or handle of the carriage being broken away. Fig. II is a vertical central longitudinal section. Fig. III is a side view of the carriage shown in Figs. I and II collapsed. Fig. IV is an inverted view of the structure shown in Fig. I erected. Fig. V is a rear view of the structure 60 collapsed, the wheels being omitted. Fig. VI is a detail perspective view showing details of the wheel support collapsing and erecting means, the wheels being omitted. Fig. VII is an enlarged detail perspective 65 view of the front end of the carriage with the parts in their erected position. Fig. VIII is an enlarged detail side view showing the arrangement of the lock, the lock being shown in its disengaged position by 70 dotted lines. Fig. IX is an enlarged detail section on a line corresponding to line 9-9 of Figs. IV and V, showing details of the mounting of the wheel supports. Fig. X is an enlarged detail section on a line corresponding to line 10-10 of Figs. IV and V, 75 showing further details of the wheel support mountings.

In the drawing similar reference characters refer to similar parts throughout the 80 several views, and the sectional views are taken looking in the direction of the little arrows at the ends of the section lines.

Referring to the drawing, we provide a main or running gear frame 1 which, in 85 the structure illustrated, is formed of a piece of tubing bent into a U-shape, the arms of the tubing constituting the side bars 2 of the frame and the bight portion constituting the rear cross bar 3, the ends 90 of the arms being disposed forwardly. The wheels 4 are carried by the wheel supporting frames 5 formed of strap-like bars or members 6 and 7, the members 6 having an upwardly inclined portion at their forward 95 ends and terminating in ear portions 8 pivoted at 9 on the outwardly projecting flange-like ears 10 of the hangers 11 on the side bars. The wheel support members 7 are provided with similar ear portions 12 100 pivoted at 9 on the flange-like ear portions

10 of the rear hangers 11. The support members 7 are riveted to the horizontal portions 13 of the members 6. See Fig. VI. The horizontal portions 13 are extended 5 rearwardly to provide supporting arms for the auxiliary wheels 14. Braces 15 are provided for the arms 13, the braces being riveted at 16 to the support members 7 and to the rear ends of the arms 13. The members 7 are provided with sockets 17 for the wheel spindles 18. The braces 15 are provided with sockets 19 for the spindles 20 of the auxiliary wheels 14. With the wheel supports thus pivotally supported on the main frame they are adapted to be swung under the frame and the wheels collapsed one upon the other, as shown in Fig. V, or to erected position, as shown in Figs. I and IV. The wheel supports are collapsed and 20 erected by means of the levers 21 which are pivoted at 22 on the side bars of the running gear frame. These levers are connected by the cross bar 23 which, in the structure illustrated, is formed integrally therewith. This crossbar is provided with offsets or shoulders 25 and 26. The part 24 of the bar between the offsets or shoulders 25 and 26 is distorted or twisted so that the shoulder 26 is in advance of the shoulder 25. The wheel supports are connected to the cross bar 23 of the collapsing levers by means of the links 27 and 28. These links are pivoted to the supports at 29. The links are provided with heads 30 swiveled in the shoulders or offsets 25 and 26 of the cross bar 23.

With the parts thus connected the swinging of the levers 21 on their pivots 22 swings the wheel supports on their pivots 40 to erect and collapse the same, the rearward movement of the levers collapsing the wheel supports and the forward movement erecting the same. The links are connected to the levers so that the wheel support actuated by the link 27 is collapsed in advance 45 or under the other wheel support.

The levers 21 are connected by the links 31 to the arms 32 of the tongue or handle 33, the handle being rigidly secured to the 50 arms which are provided with inwardly and forwardly projecting extensions 34 secured to the sides of the handle by the rivets 35. The links are connected to the arms of the tongue in front of its pivots 36 by the pivots 36'. With these connections, when the tongue is swung upwardly and rearwardly or collapsed the levers 21 are 55 swung rearwardly to collapse the wheel supports. When the tongue is swung forwardly or extended the levers 21 are swung forwardly to erect the wheel supports.

Pivoted on the arms 32 is a bail shaped lock or catch 37 having notches therein adapted to engage the ends 39 of the bars 2 60 of the running gear frame, the ends constit-

tuting keepers for the catch or lock. The lock is held yieldingly in engagement with the keeper members 39 of the frame by means of the coiled spring 40 one end of which is secured to the lock and the other 70 to the tongue. The lock may be disengaged by pressing rearwardly thereon with the foot and swinging the tongue 33 of the carriage rearwardly.

We provide a foot rest consisting, in the 75 structure illustrated, of a pair of side bars 41 pivoted at their rear ends to the bail-like hanger 42 which is pivoted at 43 to the links 31. The forward portions 44 of the side bars 41 are pivoted at 45 to the 80 rearwardly and downwardly projecting arms 46 on the tongue 33. The side bars 41 are provided with a downwardly and forwardly projecting extension forming a standard 47, the extension in the structure 85 illustrated being formed integrally with the rear portion of the foot rest side bars. Suitable slats 48 are carried by the side bars. The standard 47 projects downwardly so as to support the front end of 90 the carriage when at rest.

When the carriage is collapsed the foot rest, owing to its rear link connection to the links 31 and its connection to the projecting arms 46 on the tongue, is raised somewhat as shown in Fig. III, in which position the front end of the frame and the standard form supports or rests for the carriage.

The seat 49 is supported by the S-shaped 100 springs 50 at its rear end and the bar springs 51 at its front end, the springs 51 being formed of flat bars having one quarter twists therein, the lower ends of the springs being pivoted at 52 to the front spring 105 hangers 53. The lower ends of the rear springs 50 are carried by the rear spring hangers 54 having inwardly projecting pin-like supports 55 on which the springs are mounted. The seat spring structure is substantially that shown in the application for Letters Patent of the applicant Spofford, filed October 4, 1910, Serial No. 585,244.

The back 56 is pivoted at 61 to the brackets 62 on the seat. The back is provided 115 with segments 63 by which it is supported to be adjusted to different erected positions and so as to be collapsed forwardly on the seat, as shown in Fig. II, the back support being substantially that shown in the Cleveland Patent No. 1,048,495, dated December 31, 1912.

The side bars 57 for the seat are carried by the pivoted uprights 58 and the upper ends of the levers 21 which are extended 125 above the running gear frame for that purpose. This supports the side bars 57 so that when the wheels are collapsed the side bars are collapsed forwardly, as shown in Fig. III.

The wheels 4 are provided with guards or fenders 59 which are mounted on the main side bars over the wheels.

With the parts thus arranged the carriage is very easily collapsed and erected. To erect the same when collapsed as shown in Fig. III it is only necessary to swing the handle forwardly or the body from the handle. This may be accomplished by supporting by the handle and allowing the body to swing down by resting the carriage on the standard and allowing the body of the carriage to swing down. As the tongue is extended the connections therefor to the wheel supports swing the wheel supports to their erected position. Ordinarily the weight of the carriage is sufficient to accomplish this, but if not, a slight downward jerk on the handle brings the parts to their erected position and permits the locking catch 37 to engage under the action of its spring 40. The back can then be swung up and adjusted as desired. To fold the carriage the back is folded forwardly upon the seat and the locking catch 37 released by pressing rearwardly thereon with the foot when the tongue is swung rearwardly or collapsed and, through its connections to the wheel supports and foot rest described, collapses the same. A convenient method of collapsing is to release the locking catch and then grasp the tongue with one hand and the rear cross bar 3 of the running gear frame with the other and swing them together.

Our improved carriage is very strong and rigid when erected and at the same time the parts are comparatively simple and economical in structure.

We have illustrated and described our improvements in the form in which we have embodied the same for the market. We have not attempted to illustrate or describe certain modifications which we contemplate as possible, as we believe the disclosure made will enable those skilled in the art to which our invention relates to embody or adapt the same as conditions may require. We desire however, to be understood as claiming our improvements specifically in the form illustrated as well as broadly within the scope of the appended claims.

Having thus described our invention, what we claim as new and desire to secure by Letters Patent, is:

1. In a collapsible carriage, the combination of a U-shaped frame disposed with its bight end rearwardly, a seat mounted on said frame, seat side bars, pivoted supports for the rear ends of said seat side bars, wheel supports mounted on said frame to collapse under the same, wheel support actuating levers pivoted on said frame, said levers being extended above said frame and constituting supports for the forward ends of the seat side bars, a tongue having arms

pivoted to the side members of said frame in a spaced relation to the front ends thereof, actuating links for said levers pivoted thereto below the lever pivots and to said tongue arms in front of their pivots, a locking catch pivotally mounted on said tongue arms and adapted to engage the front ends of the side members of said frame, and an actuating spring for said catch. 70

2. In a collapsible carriage, the combination of a U-shaped frame disposed with its bight end rearwardly, wheel supports mounted on said frame to collapse under the same, wheel support actuating levers pivoted on said frame, a tongue pivoted to the side members of said frame in a spaced relation to the front ends thereof, actuating links for said levers pivoted to said tongue, a locking catch pivotally mounted on said tongue arms and adapted to engage the front ends of the side members of said frame, and an actuating spring for said catch. 75

3. In a collapsible carriage, the combination of a U-shaped frame disposed with its bight end rearwardly, wheel supports mounted on said frame to collapse under the same, wheel support actuating levers pivoted on said frame, a tongue pivoted to the side members of said frame in a spaced relation to the front ends thereof, actuating links for said levers pivoted to said tongue, a bail-shaped locking catch pivotally mounted on said tongue arms and adapted to engage the front ends of the side members of said frame, and an actuating spring for said catch. 90

4. In a collapsible carriage, the combination of a frame, a seat mounted on said frame, seat side members, wheel supports mounted on said frame to collapse under the same, means for erecting and collapsing said wheel supports comprising levers pivoted on said frame, said levers being extended above said frame and constituting supports for said seat side members, a tongue pivoted to said frame, links connecting said levers to said tongue. 105

5. In a collapsible carriage, the combination of a frame, wheel supports mounted on said frame to collapse under the same, means for erecting and collapsing said wheel supports comprising levers pivoted on said frame, a tongue pivoted to said frame, links connecting said levers to said tongue. 110

6. In a collapsible carriage, the combination of a frame, wheel supports mounted on said frame to collapse under the same, means for erecting and collapsing said wheel supports comprising levers pivoted on said frame, a tongue pivoted to said frame, links connecting said levers to said tongue, and a locking catch pivotally mounted on said tongue and adapted to engage when the tongue is extended. 125

7. In a collapsible carriage, the combination of a frame, wheel supports mounted on said frame to collapse under the same, means for actuating said wheel supports comprising levers mounted on said frame, a tongue pivoted on said frame to collapse thereon, links connecting said levers to said tongue whereby the levers are actuated to erect and collapse the wheel supports when the tongue is extended and collapsed, means for securing said tongue in its extended position, a foot rest hanger pivotally mounted on said links, downwardly projecting foot rest supporting arms on said tongue, a foot rest mounted on said foot rest hanger and said foot rest supporting arms, and a standard carried by said foot rest.
8. In a collapsible carriage, the combination of a frame, wheel supports mounted on said frame to collapse under the same, means for actuating said wheel supports comprising levers mounted on said frame, a tongue pivoted on said frame to collapse thereon, links connecting said levers to said tongue whereby the levers are actuated to erect and collapse the wheel supports when the tongue is extended and collapsed, means for securing said tongue in its extended position, a foot rest hanger pivotally mounted on said links, downwardly projecting foot rest supporting arms on said tongue, and a foot rest mounted on said foot rest hanger and said foot rest supporting arms.
9. In a collapsible carriage, the combination of a frame, wheel supports mounted on said frame to collapse under the same, a tongue pivoted on said frame, means for actuating said wheel supports comprising links connected to said tongue, a foot rest hanger pivotally mounted on said links, a foot rest supporting arm on said tongue, a foot rest mounted on said foot rest hanger and said foot rest supporting arm, and a standard carried by said foot rest.
10. In a collapsible carriage, the combination of a frame, wheel supports mounted on said frame to collapse under the same, a tongue pivoted on said frame, means for actuating said wheel supports comprising links connected to said tongue, a foot rest hanger pivotally mounted on said links, a foot rest supporting arm on said tongue, and a foot rest mounted on said foot rest hanger and said foot rest supporting arm.
11. In a collapsible carriage, the combination of a frame, wheel supports mounted on said frame to collapse under the same, means for actuating said wheel supports comprising levers mounted on said frame, a collapsible tongue, links connecting said levers to said tongue whereby the levers are actuated to erect and collapse the wheel supports when the tongue is extended and collapsed, a foot rest, a pivoted hanger for the rear end of said foot rest, a supporting

arm on said tongue for the front end of said foot rest, and a standard carried by said foot rest.

12. In a collapsible carriage, the combination of a frame, wheel supports mounted on said frame to collapse under the same, means for actuating said wheel supports comprising levers mounted on said frame, a collapsible tongue, links connecting said levers to said tongue whereby the levers are actuated to erect and collapse the wheel supports when the tongue is extended and collapsed, a foot rest, a pivoted hanger for the rear end of said foot rest, and a supporting arm on said tongue for the front end of said foot rest.

13. In a collapsible carriage, the combination of a frame, wheel supports mounted on said frame to collapse under the same, means for actuating said wheel supports comprising a lever mounted on said frame, a tongue pivoted on said frame, links connecting said lever to said tongue whereby the lever is actuated to erect and collapse the wheel supports when the tongue is extended and collapsed, a foot rest, said foot rest having operative connections to said tongue so that it is moved toward and from the frame as the tongue is extended and collapsed, and a standard carried by said foot rest.

14. In a collapsible carriage, the combination of a frame, wheel supports mounted on said frame to collapse under the same, means for actuating said wheel supports comprising a lever mounted on said frame, a tongue pivoted on said frame, links connecting said lever to said tongue whereby the lever is actuated to erect and collapse the wheel supports when the tongue is extended and collapsed, and a foot rest, said foot rest having operative connections to said tongue so that it is moved toward and from the frame as the tongue is extended and collapsed.

15. In a collapsible carriage, the combination of a frame, wheel supports mounted on said frame to collapse under the same, means for actuating said wheel supports comprising a tongue mounted on said frame to collapse rearwardly thereon, said tongue having operative connections with said wheel supports whereby they are erected and collapsed, a movable foot rest having operative connection with said tongue whereby the foot rest is moved toward and from the frame when the tongue is collapsed and extended, and a standard carried by said foot rest.

16. In a collapsible carriage, the combination of a frame, wheel supports mounted on said frame to collapse under the same, means for actuating said wheel supports comprising a tongue mounted on said frame to collapse rearwardly thereon, said

5 tongue having operative connections with said wheel supports whereby they are erected and collapsed, and a movable foot rest having operative connection with said tongue whereby the foot rest is moved toward and from the frame when the tongue is collapsed and extended. 70

10 17. In a collapsible carriage, the combination of a frame, collapsible wheel supports mounted on said frame, means for actuating said wheel supports, a collapsible foot rest, means for erecting and collapsing said foot rest as the wheel supports are collapsed and erected, and a standard rigidly mounted 75 on said foot rest. 80

15 18. In a collapsible carriage, the combination of a frame, wheel supports mounted on said frame to collapse under the same, means for actuating said wheel supports comprising levers pivoted on said frame, a tongue pivoted on said frame, links connecting said levers to said tongue whereby the wheels are actuated to erect and collapse the wheel supports as the tongue is 85 extended and collapsed, a foot rest mounted on said links and tongue to be moved to and from the frame as the tongue is extended and collapsed, and a standard rigid with said foot rest, the said standard coacting 90 with the front end of the frame when the carriage is collapsed to provide a base or support therefor. 95

20 19. In a collapsible carriage, the combination of a frame, wheel supports mounted on said frame to collapse under the same, means for actuating said wheel supports comprising a tongue pivoted on said frame, a collapsible foot rest, operative connections for said tongue to said foot rest whereby the 100 foot rest is extended and collapsed as the tongue is extended and collapsed, and a standard carried by said foot rest, said standard being adapted when the rest is collapsed to coact with the forward end of the frame to form a support for the carriage. 105

25 20. In a collapsible carriage, the combination of a frame, wheel supports pivoted on said frame to collapse under the same, actuating levers pivoted on said frame, said 110 levers being connected by a bar having offsets therein, said offsets being offset relative to each other so that one is in advance of the other, links pivotally secured to said wheel supports and swiveled in said offsets 115 of said cross bar, a tongue having arms pivoted to the side members of said frame, actuating links for said levers pivoted thereto, and to said tongue arms in front of their pivots, and a locking catch for said tongue. 120

30 21. In a collapsible carriage, the combination of a frame, wheel supports pivoted on said frame to collapse under the same, actuating levers pivoted on said frame, said levers being connected by a bar, links pivotally secured to said wheel supports and 125

swiveled in said cross bar, a tongue having arms pivoted to the side members of said frame, actuating links for said levers pivoted thereto, and to said tongue arms in front of their pivots, and a locking catch 70 for said tongue. 75

22. In a collapsible carriage, the combination of a frame, wheel supports pivoted on said frame to collapse under the same, actuating levers pivoted on said frame, said 80 levers being connected by a bar having offsets therein, said offsets being offset relative to each other so that one is in advance of the other, links pivotally secured to said wheel supports and swiveled in said offsets 85 of said cross bar. 90

23. In a collapsible carriage, the combination of a frame, wheel supports pivoted on said frame to collapse under the same, actuating levers pivoted on said frame, said 85 levers being connected by a bar, links pivotally secured to said wheel supports and swiveled in said cross bar. 95

24. In a collapsible carriage, the combination of a frame, wheel supports pivoted on said frame to collapse under the same, actuating levers pivoted on said frame, said levers being connected by a cross bar, links connecting said wheel supports to said cross bar, a tongue pivoted to said frame, links 90 connecting said levers to said tongue, and means for locking the parts in their erected position. 95

25. In a collapsible carriage, the combination of a frame comprising side members, 100 wheel supports pivoted on said frame to collapse under the same, actuating levers pivoted on said frame side members to extend below the same, said levers being connected at their lower ends by a cross bar, 105 and links connecting said wheel supports to said cross bar. 110

26. In a collapsible carriage, the combination of a frame, wheel supports mounted on said frame to collapse under the same, means for actuating said wheel supports comprising a tongue mounted on said frame to collapse rearwardly thereon, and a collapsible foot rest having operative connection with said tongue whereby the foot rest 115 is collapsed and extended when the tongue is collapsed and extended. 120

27. In a collapsible carriage, the combination of a frame, a tongue pivoted on said frame to collapse thereon, a foot rest, a pivoted hanger for the rear end of said foot rest, a supporting arm on said tongue for the front end of said foot rest, and a standard carried by said foot rest. 125

28. In a collapsible carriage, the combination of a frame, a tongue pivoted on said frame to collapse thereon, a foot rest, a pivoted hanger for the rear end of said foot rest, and a supporting arm on said tongue 130 for the front end of said foot rest. 120

29. In a collapsible carriage, the combination of a frame, a tongue pivoted on said frame to collapse thereon, a collapsible foot rest, and arms on said tongue to which said foot rest is connected, said arms being disposed relative to the tongue pivot so that the movement of the foot rest and tongue are opposite in the collapsing and erecting of the same.
- 10 30. In a collapsible carriage, the combination of a frame, a tongue pivoted on said frame to collapse rearwardly thereon, arms on said tongue, and a collapsible foot rest connected at its front end to said arms on said tongue, said arms disposed so that they are swung upwardly and forwardly when the tongue is collapsed.
- 15 31. In a collapsible carriage, the combination of a frame, a tongue pivoted on said frame to collapse thereon, downwardly projecting arms on said tongue, and a standard pivotally connected to said arms so that it is swung to and from its extended position by the collapsing and erecting of the tongue.
- 20 32. In a collapsible carriage, the combination of a frame, a collapsible tongue, a collapsible foot rest, a standard, and operative connections for said foot rest and standard to said tongue whereby said foot rest and standard are swung to and from extended position as the tongue is swung to and from its extended position.
- 25 33. In a collapsible carriage, the combination of a frame, wheel supports mounted on said frame to collapse under the same, means for actuating said wheel supports, a collapsible foot rest, operative connections for said foot rest to said wheel support actuating means whereby the foot rest is extended and collapsed, and a standard carried by said foot rest, said standard being adapted when the carriage is collapsed to coact with the front end of the carriage to form a support for the carriage.
- 30 34. In a collapsible carriage, the combination of a frame, wheel supports mounted on said frame to collapse under the same, means for actuating said wheel supports, a collapsible foot rest, operative connections for said foot rest to said wheel support actuating means whereby the foot rest is extended and collapsed, and a standard carried by said foot rest, said standard being adapted when the carriage is collapsed to constitute a member for supporting the carriage on end.
- 35 35. In a collapsible carriage, the combination of a frame, wheel supports mounted on said frame to collapse under the same, means for actuating said wheel supports, a collapsible foot rest, operating connections for said foot rest to said wheel support actuating means whereby the foot rest is extended and collapsed, and a standard, said standard to said wheel support actuating means whereby the standard is extended and collapsed, said standard when the carriage is collapsed constituting a member for supporting the carriage on end.
- 40 36. In a collapsible carriage, the combination of a frame, wheel supports mounted on said frame to collapse under the same, means for actuating said wheel supports, a standard, operating connections for said standard to said wheel support actuating means whereby the standard is extended and collapsed, said standard when the carriage is collapsed constituting a member for supporting the carriage on end.
- 45 37. In a collapsible carriage, the combination of a frame, a tongue pivoted to said frame to collapse thereon, a foot rest, a standard rigidly mounted on said foot rest, operative connections for said tongue to said foot rest whereby the foot rest is erected and collapsed with the erecting and collapsing of the tongue, said standard when the carriage is collapsed constituting a member for supporting the carriage on end.
- 50 38. In a collapsible carriage, the combination of a frame, a collapsible foot rest, means for erecting and collapsing said foot rest, and a standard rigidly mounted on said foot rest, said standard constituting a member for supporting the carriage on end when the carriage is collapsed.
- 55 39. In a collapsible carriage, the combination of a frame, collapsible wheel supports mounted on said frame, means for actuating said wheel supports, a standard, operating connections from said standard to said means for actuating said wheel supports whereby the standard is swung to and from its extended position with the erecting and collapsing of the wheel supports, said standard constituting a member for supporting the frame on end when in collapsed position, and a support for one end of the frame when in its extended position.

In witness whereof we have hereunto set our hands and seals in the presence of two witnesses.

COLLAPSIBLE CARRIAGE. Patent dated November 23, 1915. Disclaimer filed
July 19, 1916, by the assignee, *Sturgis Steel Go-Cart Co.*

Enters this disclaimer—

“To claims 5, 14, 16, 26 and 32 of the said Letters Patent, which claims are in
the following words, to wit:

“5. In a collapsible carriage, the combination of a frame, wheel supports mounted
on said frame to collapse under the same, means for erecting and collapsing said
wheel supports comprising levers pivoted on said frame, a tongue pivoted to said
frame, links connecting said levers to said tongue.

“14. In a collapsible carriage, the combination of a frame, wheel supports
mounted on said frame to collapse under the same, means for actuating said wheel
supports comprising a lever mounted on said frame, a tongue pivoted on said frame,
links connecting said lever to said tongue whereby the lever is actuated to erect
and collapse the wheel supports when the tongue is extended and collapsed, and a
foot rest, said foot rest having operative connections to said tongue so that it is
moved toward and from the frame as the tongue is extended and collapsed.

“16. In a collapsible carriage, the combination of a frame, wheel supports
mounted on said frame to collapse under the same, means for actuating said wheel
supports comprising a tongue mounted on said frame to collapse rearwardly thereon,
said tongue having operative connections with said wheel supports whereby they
are erected and collapsed, and a movable foot rest having operative connection with
said tongue whereby the foot rest is moved toward and from the frame when the
tongue is collapsed and extended.

“26. In a collapsible carriage, the combination of a frame, wheel supports
mounted on said frame to collapse under the same, means for actuating said wheel
supports comprising a tongue mounted on said frame to collapse rearwardly thereon,
and a collapsible foot rest having operative connection with said tongue whereby
the foot rest is collapsed and extended when the tongue is collapsed and extended.

“32. In a collapsible carriage, the combination of a frame, a collapsible tongue,
a collapsible foot rest, a standard, and operative connections for said foot rest and
standard to said tongue whereby said foot rest and standard are swung to and
from extended position as the tongue is swung to and from its extended position.”
